HAIR HOLDER

Siegfried Behr, Flushing, N. Y.

Application September 4, 1951, Serial No. 244,921

1 Claim. (Cl. 132—46)

1

This invention relates to holders for holding a lady's hair in combed condition.

In spite of the orderliness and tidiness of the ordinary type of hair coiffure, stray hairs get out of place and fall on the face and neck of the individual especially when the individual is out in the wind and weather or when doing household chores. Tying ribbons and the use of other expedients for preventing this condition are bothersome, time consuming, unimaginative, and require considerable skill.

It is an object of the present invention to provide a holder that effectively holds the hair in combed condition and prevents it from becoming displaced and tangled.

Another object is to provide a holder of this kind that is easily mounted on and demounted from the hair.

Another object is to provide a hair holder of this kind that is neat and attractive in appearance.

Another object is to provide a hair holder of this kind that is simple in construction and economical to manufacture.

Other objects and advantages of the invention will be apparent from the description thereof to follow taken in connection with the accompanying drawing in which—

Fig. 1 is a side view of a lady's hair-do with a holder embodying the invention in position thereon.

Fig. 2 is a top plan view of the holder shown in full lines in closed position and in dotted lines in open position.

Fig. 3 is a cross-sectional view taken on the plane of the line 3—3 of Fig. 2.

Fig. 4 is a side view of the holder.

Fig. 5 is a front view thereof.

Referring to the drawing, a brush-back "hair-do" or style of hair coiffure is shown formed with a knot or tuft 6 at the back of the neck and a holder 7 on the hair in front of the knot.

The holder comprises a pair of separable semi-annular metallic bands 8 and 9 hingedly connected together at one of their ends with their other ends free and normally in edge to edge contact as shown in Fig. 2, forming a ring. The hinged connection comprises a plate 10 secured at one end to the end of the band 9, the other free end of the plate having perforated ear portions 11 on the opposed edges. A pivot pin 12 is supported by and between the ear portions 11. A plate 13 is secured at one end to the adjacent end of the band 8, its opposite end being formed with looped bearing portions 14 encircling the pin

2

12 intermediate its ends. A coiled spring 15 encircles the pivot pin 12 between the bearing portions 14 of the band 8. One free end of the spring presses against the plate 10 on band 9 and its other free end against the plate 13 on band 8 to urge the bands to closed relation, as shown in Fig. 2. Wing members 16 are secured to the hinged ends of the bands and extend in opposite directions thereby serving as finger pieces for moving the bands 8 and 9 on their hinge support to separate and move the free ends to open position as shown in dotted lines in Fig. 2. It will be understood that the finger pieces may be made in any desired shape.

15 Mounted on the inner surface of each of the bands 8 and 9 is a row of projections or teeth 17, the rows being in alignment.

The bands and finger pieces are preferably formed of metal but may be made of any suitable material.

In use, the holder is mounted on the neck portion of the hair-do in front of the knot as shown in Fig. 1. This is easily done by pressing the finger pieces 16 toward each other whereby the bands 8 and 9 will be moved away from each other against the action of spring 15 so that said bands are separated to permit the hair to be inserted therebetween. When the hair is positioned inside the bands, the pressure on the finger pieces is released and the bands will be moved by the spring 15 toward each other bringing their free ends into contact and bringing the teeth 17 into biting contact with the hair thereby holding all of the strands of hair against displacement, and at the same time holding the holder against displacement.

The holder is easily removed from the hair by merely pressing the finger pieces toward each other to open the bands and then withdrawing the holder from the hair.

I claim:

A holder for lady's hair comprising a pair of semi-annular bands hingedly connected together at one end for swinging movement toward and away from each other to closed and open positions, respectively, said bands when in closed position cooperating to form a ring and when in open position being adapted to receive a bunch of hair therebetween, said hinge connection including plates integral with the adjacent ends of the bands and extending toward each other, a pin extending through the extensions of said plates, a coiled spring encircling said pin and having oppositely disposed free ends, one of said free ends 50 pressing against one of said plates, the other of

said free ends pressing against the other of said plates whereby the ends of the bands opposite the hinge ends are urged into edge to edge engagement, aligned clusters of teeth on the inner surfaces of said bands adapted to be embedded in the hair for holding the strands of hair in combed position and finger pieces integral with the bands extending in opposite directions for moving the bands to open position.
